UNITED STATES PATENT OFFICE.

FLORIS GOUBERT, OF PARIS, FRANCE.

SNAP-FASTENER.

1,252,261.

Specification of Letters Patent. Patented Jan. 1, 1918.

Application filed September 21, 1917., Serial No. 192,595.

To all whom it may concern:

Be it known that I, FLORIS GOUBERT, a citizen of the Republic of France, residing at Paris, France, have invented certain new and useful Improvements in Snap-Fasteners, of which the following is a specification.

The present invention relates to snap fasteners; and it comprises, briefly, an improved device of the general character specified, which may be cheaply manufactured and readily manipulated, and which will serve to rigidly hold together the parts to which it is applied.

According to the invention, the improved fastener consists of two members which are exact counterparts of each other, instead of the differently-shaped male and female members ordinarily employed; and each of these members is provided, in turn, with a pair of specially-constructed parts for co-action with those of the other member, so that a double snap interlock is thereby produced which holds the members together with sufficient tenacity to completely preclude their accidental disengagement. By virtue of such construction, it is possible to construct both members of the fastener with the same dies or other machinery, instead of requiring separate dies for each member, as is more usually the case, so that the cost of production is very considerably reduced.

An embodiment of the invention is illustrated in the accompanying drawing, in which:

Figure 1 is a transverse sectional view of the improved fastener, showing the members interlocked.

Figs. 2 and 3 are side elevations, of the two members.

Fig. 4 is a bottom plan view of Fig. 3.

Fig. 5 is a perspective view, showing the members secured to the fabric or other parts which are to be fastened together.

As previously stated, the fastener of the present invention consists of two separate members or devices which are exact counterparts of each other. Each of these members is constructed of thin sheet metal, or other suitable sheet material of resilient character, and in the form illustrated, comprises a plate *a*, which may, or may not, be ornamented and which is secured in any suitable manner to the fabric or other strip whereon the fastener is to be used. This plate *a* is cut or stamped out in such a way

as to provide at one end a tongue *b*, which is rolled back upon itself to form a tubular bead, of substantially cylindrical or other suitable shape, and at the other end a lip or tongue *c*, which is likewise rolled back, the edges *b'* and *c'* of the parts *b* and *c* being free. The said parts *b* and *c* are disposed parallel with each other, and they may, of course, have any desired length, depending upon the character and size of the particular article to which the fastener is to be attached.

In use, the two members of the fastener are arranged upon the parts to be connected in such a way that when said members are pressed face to face against each other, the bead *b* of each member will snap into the lip *c* of the other member, owing to the fact that the bead is more nearly closed than the lip, and will be gripped thereby and held against displacement, so that the members may be considered, in a sense, as reversed with respect to each other. The formation of the lips and beads of resilient material, and the fact that their respective edges *b'* and *c'* are left free, enable them to yield slightly during the coupling action, after which they tend to assume their normal positions, so that a double spring-interlock or grip is thus provided, as will be understood. The disengagement of the two members may likewise be readily effected, owing to the resilience of the locking parts *b* and *c*, by merely pressing or pulling the outer member away from the inner member.

While each pair of locking parts *b* and *c* has been here shown as provided upon a single plate, it will be understood that such parts may be separately constructed, in which case they will be furnished with foundation or attaching pieces of some character, specific illustration thereof being omitted as unnecessary.

I claim as my invention:

1. A snap fastener, comprising two exactly counterpart members, each embodying a substantially-cylindrical part and a gripping part disposed parallel therewith, said members being adapted for arrangement reversely with respect to each other, so that the gripping part on each member will engage the cylindrical part on the other member.

2. A snap fastener, comprising two exactly counterpart resilient members, each embodying a substantially-cylindrical part

100

105

110

and a recessed gripping part integrally connected with the cylindrical part and disposed parallel therewith, said members being adapted for arrangement reversely with respect to each other, so that the cylindrical part on each member may be forced into the gripping part in the other member.

3. A snap fastener, comprising two exactly - counterpart members, each embodying a longitudinally-split, cylindrical bead

and a spring lip disposed parallel with the bead and having substantially the same transverse curvature, said members being adapted for arrangement reversely with respect to each other, so that the lip on each member may be snapped over the bead on the other member.

In testimony whereof I affix my signature.

FLORIS GOUBERT.
